UNITED STATES PATENT OFFICE.

WILLIAM H. SCHULZE, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A RADIATOR CAP.

Application filed April 18, 1925. Serial No. 13,161. Term of patent 7 years.

To all whom it may concern:

Be it known that I, WILLIAM H. SCHULZE, a citizen of the United States, residing in the city of Chicago, in the county of Cook and State of Illinois, have invented a new, original, and ornamental Design for a Radiator Cap, of which the following is a specification, reference being had to the accompanying drawings, forming a part thereof.

In the drawings:—

Figure 1 is a side elevation of a radiator cap embodying my new design.

Figure 2 is a top plan view of the same.

Figure 3 is a front elevation of the cap shown in Figures 1 and 2.

I claim:

The ornamental design for a radiator cap substantially as shown.

In testimony whereof, I have hereunto set my hand, at Chicago, Illinois, this 16th day of April, 1925.

WILLIAM H. SCHULZE.
